Application October 13, 1937, Serial No. 168,739
Renewed April 6, 1940

4 Claims. (Cl. 24—123)

This invention relates to improvements in rope clips and more particularly to means for joining intersecting ropes.

In the fabrication of rope nets and other reticulate fabrics it has been the practice to form involved knots at the points of the intersecting ropes to prevent them slipping relative to each other. This method, limited as it is to hand tying, requires very skilled labor, is tedious, costly, and lacking in uniformity. In addition to the disadvantage of the extra length and weight involved in such knots, the knots themselves are subject to undue wear because of their bulk.

Among the objects of the invention is to provide mechanical means for joining the overlying ropes of reticulate fabrics without knotting.

Another object is to clamp the overlying ropes within a metal clip that is simple, compact, and easily applied by pressure.

Another object is to compress tightly the overlying ropes within the clips to prevent slippage therein.

Another object is to reinforce the clips so that they will maintain the applied pressure.

Another object is to protect the juncture of the ropes against wear.

Another object is to avoid crystallization and resultant cracking of the clinching lugs of the assembled rope clips.

Another object is to assure uniformity in the meshes of reticulate fabrics.

Other objects and advantages will appear as the description progresses.

In this specification and the accompanying drawings, the invention is disclosed in its preferred form. But it is to be understood that it is not limited to this form because it may be embodied in other forms within the purview of the claims following the description.

In the two sheets of drawings:

Fig. 1 is a plan view of the juncture of two overlying ropes joined in accordance with this invention, two of the clinching lugs being broken away to better illustrate the underlying structure.

Fig. 2 is a side view of the same in vertical section taken along the line II—II, Fig. 1.

Fig. 3 is an oblique section taken on the line III—III, Fig. 1.

Fig. 4 is a side elevation detail of the crown plate.

Fig. 5 is a plan view from above of the clinch plate.

Fig. 6 is a fragmentary detail in vertical sec-

tion of one corner of the clinch plate, taken on the line III, Fig. 1.

Fig. 7 is a similar view of the same with the associated portion of the crown plate in place and the bending of the clinching lug in progress.

Fig. 8 is a plan view from above of the crown plate, modified by the addition of non-slip embossments.

Fig. 9 is a cross section of the same on the line IX—IX, Fig. 8.

In detail the structure illustrated in the drawings, referring first to Fig. 5, comprises a rectangular metal plate having the groove 1 struck down into the body of the plate by forming dies. The groove has the semi-cylindrical necks 3, 4 at 15 opposite ends thereof. The longer necks 5, 6 intersect the central portion of the groove 1 at right angles thereto. The necks 5, 6 are elevated above the bottom of the groove 1. The necks terminate in the flaring edges 7, 8, 9, and 10 respectively.

The four corners 11, 12, 13, 14 of the plate are struck upward by dies, perpendicular to the plane 15 of the plate, to form clinching lugs. The triangular ends 11', 12', 13', and 14' of the lugs are 25 bent outward, see Figs. 5, 6, 7.

The octagonal crown plate shown in Figs. 1, 2, and 4 is similar in every respect to the clinch plate, except that the clinching lugs 11—14 are omitted. It comprises the groove 1' with the 30 necks 3', 4' at its opposite ends. The necks 5', 6' intersect the central portion of the groove 1'. The necks are flared outward to form the bell-like ends 7', 8', 9', and 10'. The planes 15' are flanged upward to form the struts 11'', 12'', 13'', 35 and 14'' between the bell ends 7', 8', 9', and 10' of the crown plate.

In assembling the opposed plates, the rope A is laid in the groove 1 in the clinching plate, and the rope B overlies it in the crossed groove 1' in 40 the crown plate which is placed on top of the crossed ropes so that the four edges 11'', 12'', 13'', 14'' lie within the four clinch lugs 11—14, with the rope B within the groove 1', which is transverse to the groove 1 in the clinch plate 15. 45

These lugs 11'—14' are then bent inward by lateral dies such as y, see Fig. 7. When the bending operation is partially effected, the dies y are backed away. The bending operation is completed by a clinching tool which is forced downwardly against the clinching lugs from above under considerable pressure. It is important that the pressure of the clinching tool be applied only against the angularly offset triangular planes 11', 12', 13', and 14' of the lugs and direct 50

pressure on the bends be avoided. The resulting bends are of wide radius as shown in Fig. 3. This precludes destructive strains in the bent portions of the clinching lugs and cracking resulting from crystallization thereof.

This pressure forces the ropes A, B into their respective grooves and bends them across each other and also clamps the several necks 3, 4, and 5, 6 tightly around the ropes where they emerge 10 from the clip. This clamping action and the friction between the overlying ropes prevents any relative movement between the ropes which are tightly compressed and completely fill the space within the clip, as shown in Fig. 2.

15 The struts 11"-14" assist in maintaining the compression of the rope fibers clinched within the clip by preventing the flattening or distortion of the necks 1-4 when the clinching die pressure is released. The struts also reinforce the clinched 20 clip to prevent moisture swollen rope from opening the clinch or distorting the clip so that it is loose when the rope dries out. A further advantage of the struts is the enabling of the increased radius of the bends 11-14, see Fig. 3, in 25 clinching the lugs over these struts as discussed above. The struts, being locked within the bends of the clinching lugs, prevent the planes 15' from slipping from under the clinching lugs should heavy forces be applied to the ropes tending to 30 force the clinch and crown plates apart.

The bell shape ends of the several necks as at 7-10 and 7'-10' prevent the edges of the clip 35 fraying the ropes A-B where they extend from the clip.

35 The combined plates are shaped so that their respective grooves conform to the juncture of the ropes and are of such depth that they compress the juncture when the plates are finally joined. When twisted rope is under tensile strain 40 it reduces in diameter. It is therefore necessary to put the juncture of the cross ropes A, B, under compression sufficient to prevent this reduction of cross section within the clips. The struts 11"-14" make this compression possible with thinner gage metal clips. Thicker metal tends 45 to fracture at the clinch bends, often breaking away entirely during fabrication or later. Small cracks permit corrosion to further weaken the clinch.

50 The embossed tits 16-16 may be provided as shown in Fig. 8 and 9 to increase the compression and firmly anchor the crossed ropes in the clips.

They also counteract the tendency of the twisted rope to rotate and "unscrew" from the clips while under tension and reduced in diameter.

Where the cross ropes join the side rope, the ends of the cross ropes can be cut off flush with 5 the neck 3 if desired, as indicated by the dotted line x in Fig. 1.

The clips can be used to fasten the cross rungs in rope ladders, drapers, and the like, by inserting the rung ends into the neck 4 and between 10 the strands of the single rope before clinching the clip on to the rope.

In forming drapers, rope slings, etc., where it is desired to reinforce a sheet of canvas or screen with a reticulate net, the clinching lugs 11-14 15 are forced up through the canvas before the crown plate is clinched therein.

The ingenuity of those skilled in the art in applying this clip to rope, wood and metal rods, wire, cable, etc., will suggest uses and advantages 20 not herein stated, without departing from the spirit of the invention.

Having thus described the invention, what is claimed and desired to be secured by letters patent is:

1. A clip such as described comprising a clinch plate and a crown plate having registering grooves formed thereon respectively; upstanding struts on said crown plate; and lugs on said clinch plate enclosing said struts respectively. 30

2. A clip such as described, comprising opposed plates each having registering grooves forming circular necks; bell-like flanges on the outer ends of said necks; upstanding struts on one of said plates between said necks respectively; and lugs 35 on the opposite plate and enclosing said struts respectively.

3. A clip such as described comprising a pair of plates having registering grooves formed therein respectively; upstanding struts on the edges of 40 one of said plates; and corner lugs on the opposite plate enclosing said strut in a curve of relatively wide radius.

4. A clip such as described comprising an octagonal crown plate; upstanding struts on said 45 plate; a clinch plate having corners enclosing said struts and lying against the plane of said crown plate; and circular necks formed by semi-circular grooves in both of said plates between said struts respectively.
